BRENNAN; Benjamin Charkow

(57) **CLAIM**

The ornamental design for a mattress pad, as shown and described.

DESCRIPTION

FIG. 1 is a bottom perspective view of the mattress pad, showing my new design;

FIG. 2 is a front elevational view of the mattress pad shown in FIG. 1;

FIG. 3 is a rear elevational view of the mattress pad shown in FIG. 1;

FIG. 4 is a left side elevational view of the mattress pad shown in FIG. 1;

FIG. 5 is a right side elevational view of the mattress pad shown in FIG. 1;

FIG. 6 is a top plan view of the mattress pad shown in FIG. 1; and,

FIG. 7 is a bottom plan view of the mattress pad shown in FIG. 1.

The dashed broken lines show portions of the article that form no part of the claimed design. The stippling shown in FIGS. 1 and 7 depicts a contrast in appearance.

1 Claim, 3 Drawing Sheets
